(57) **CLAIM**

The ornamental design for a license plate frame with soccer ball motif, as shown and described.

DESCRIPTION

FIG. 1 is a front perspective view of a license plate frame with soccer ball motif according to the present invention, showing the frame attached to a vehicle and holding a license plate.

FIG. 2 is a front perspective view thereof.

FIG. 3 is a front elevation view thereof.

FIG. 4 is another front perspective view thereof.

FIG. 5 is another front elevation view thereof.

FIG. 6 is a rear elevation view thereof.

FIG. 7 is a left side elevation view thereof.

FIG. 8 is a right side elevation view thereof.

FIG. 9 is a top view thereof; and,

FIG. 10 is a bottom view thereof.

The broken line showing is for the purpose of illustrating environmental subject matter and forms no part of the claimed design.
